ELECTRIC DISCHARGE DEVICE AND
METHOD OF OPERATION

Eugene Lemmers, Cleveland Heights, Ohio, assignor to General Electric Company, a corporation of New York

Application August 1, 1941, Serial No. 405,060

9 Claims. (Cl. 315—174)

This invention relates to electric discharge devices and their operation, and involves novelty in the control of electric discharges. One advantage that can be obtained through the invention is the elimination of troublesome accessories, including starting and current-limiting means like ballasts, thermal cut-out switches, etc. Another advantage is improvement of the voltage-current characteristics of electric discharge devices, especially discharge devices containing gas or vapor, even to the extent of enabling such devices to start and operate with a positive overall voltage-current characteristic, and without resort to specially high voltage for starting. The invention is applicable to discharge devices of suitable types already known, without necessity for any radical modification, and without need for elaborate or expensive accessories—though its range of useful capabilities can be considerably increased by the use of special features and arrangements that are referred to hereinafter. The invention may be applied to discharge devices producing useful radiations for various purposes, such as germicidal tubes or lamps, and lamps used industrially for irradiating or treating many substances and products, and for fluorescent lighting. I have hereinafter explained the invention with particular reference to a device suitable for use as a fluorescent lamp.

Very generally, electric discharge through gases and vapors display a negative resistance or voltage-current characteristic. Such characteristics are due to positive ions in the discharge atmosphere, which are a necessary accompaniment and factor of the discharge, and which act to augment it in a cumulative manner: i. e., ions once produced result in the production of more ions, which produce still more ions, etc., etc. Once the discharge is started, therefore, it automatically increases and "runs away"—unless the current is limited by means of a ballast resistor, or the like, in series with the discharge.

In the operation of one-way discharge devices on pulsating or alternating current, the discharge atmosphere is ionized or kept ionized by the periodically recurring pulses or waves of the discharge voltage and the consequent emission of electrons from a cathode electrode of the discharge device. During zero or reverse-voltage periods of the voltage cycle, the emission of electrons and the discharge itself cease, and the discharge atmosphere starts to deionize; but the voltage impulses and the resulting emissions of electrons succeed one another before there is time for total decay of ionization in the discharge at-

mosphere, and so discharge recurs, intermittently, on each voltage impulse in the proper direction. If, on the other hand, both electrodes of a discharge device are emissive, the discharge takes place in opposite directions alternately. In either case, it is the persistence of ionization in the discharge atmosphere from one voltage impulse to the next that enables the ionization and the discharge to build up cumulatively from impulse to impulse until (in the absence of extrinsic control over the current) the discharge reaches run-away proportions.

In accordance with my invention, such persistence of ionization is prevented; and if necessary, each period of discharge is additionally limited in duration so that any real runaway in a single discharge period is impossible. For this purpose, an intermittent discharge is initiated and reinitiated at such periods in the series of voltage impulses or of A. C. cycles that the duration of the discharge each time is too short for the current to attain an excessive value before the discharge is terminated by fall of the discharge voltage; while the outage interval from the resulting termination of the discharge to the initiation of the next succeeding discharge permits substantial deionization of the discharge atmosphere. If the duration of a discharge-voltage impulse or cycle is sufficiently brief, an outage interval that assures adequate or substantial deionization before the next such impulse may afford all the control necessary. The explanation of why runaway does not occur in such cases seems to be that during the part of each cycle when the discharge is going on, ions are not formed fast enough, and the envelope walls have not time to trap enough of them to come to equilibrium; while by the next ignition, the ions have decayed away: hence each firing or discharge is essentially just like the one directly before it. In other words, the intermittent main discharges remain isolated, as well as the auxiliary ionizing discharges that initiate them.

For 60-cycle A. C. current, it is found satisfactory in practice to fire or initiate one-way discharge on one peak of each cycle, which may be either the positive or the negative voltage peak: e. g., the discharge may be initiated somewhat before the voltage reaches its maximum positive value or crest, or at any time thereafter while its positive-value suffices for a discharge across the discharge gap. This may be called "quarter-cycle" operation, since the discharge endures only about one-fourth of each sine-wave period, while the remaining three-quarters is available for de-

ionization of the discharge atmosphere. Apparently the deionization time is something like $\frac{1}{60}$ second: at any rate, such quarter-cycle operation does give a positive over-all characteristic to the discharge. For A. C. current approximating 25-cycle frequency, more or less, two-way discharge likewise shows a positive characteristic when suitably initiated on each peak (positive and negative) of each cycle, since such half-cycle operation affords substantially the same length of time for deionization as does quarter-cycle operation on 60-cycle A. C.

I have found that control of ionization and discharge as above indicated can be effected very simply and directly through the agency of an auxiliary ionization of the discharge atmosphere; i. e., the atmosphere is specially ionized during such of the main voltage impulses or A. C. half-waves that the main discharge thus initiated or ignited and the ionization of the atmosphere that enables it to take place both die out, each time, before the next succeeding ionization. Besides this choice of periods in the series of main voltage impulses or half-waves which allow ionization to decay, the particular points of the impulses or half-waves where ionization is effected may be chosen according to the duration and wattage that are desired for the main discharge, as well as to allow it to die out, each time, too soon for the main discharge current to become excessive. An ionizing voltage or discharge for these purposes may be provided in various ways, a few of which I have illustrated and explained hereinafter. Such an auxiliary ionizing discharge may preferably be A. C. for the sake of simplicity of the power supply, if for no other reason. As the voltage for this auxiliary discharge need on its peaks only be just above or a little above the ionizing potential of the discharge atmosphere, and as the current required in it is but small, its control as against running away presents no serious problem: the fact that it need only fire for an instant on the peaks of the auxiliary voltage cycle tends to give it an overall positive characteristic of its own; and any extrinsic control needed is afforded by the means ordinarily employed to derive the low auxiliary voltage from the higher voltage naturally employed for the main discharge. Control of the timing of the main discharge with respect to the main voltage cycle may be effected either by adjusting the peak value of the auxiliary voltage, or by adjusting the phase relation between the main and auxiliary voltage cycles. The frequencies of these main and auxiliary pulsating or A. C. voltage cycles will, in practice, bear a simple arithmetical relation to one another, if they are not actually the same; and they will usually be approximately in phase, even when subject to slight adjustment of their phase relation for purposes of timing.

Various other features and advantages of my invention will become apparent from the following description of species and forms of embodiment, and from the drawing.

In the drawing, Fig. 1 is a diagrammatic illustration of a simple form of electric discharge device adaptable for the purposes of my invention, and of suitable electrical connections therefor; Fig. 2 is a voltage diagram illustrating the operation of the system shown in Fig. 1; Fig. 3 is a diagram similar to Fig. 1 showing two such discharge devices reversely connected, rectifier fashion, for half-cycle operation; Fig. 4 is a diagram similar to Fig. 2 illustrating the operation of the system shown in Fig. 3; and Fig. 5 is a dia-

gram similar to Figs. 1 and 3 showing a single discharge device and its connections, suitable for half-cycle operation like the two devices in Fig. 3.

Figs. 6 and 7 are diagrams illustrating simplified electrical supply systems for discharge devices like that in Fig. 1; and Fig. 8 is a similar diagram showing a somewhat different discharge device, as well as a modified system of electrical connections.

Figs. 9, 10, 11 and 12 are diagrams illustrating discharge devices similar to that of Fig. 1 with ancillary ionizing arrangements, and including electrical supply connections; Fig. 13 is a similar diagram showing modifications in the discharge device, as well as in the electrical system; and Fig. 14 is a similar diagram showing further modification of the device and of the electrical system.

Fig. 1 illustrates the application of my invention to a well-known simple type of one-way electric discharge device that comprises a vitreous tubular envelope 14 having at one end anode disc 15 connected to a lead 16 sealed through the end of the envelope, and having at its other end a cathode 17 which may be of filamentary thermionic type (such as a coiled coil of tungsten wire activated with the usual mixture of barium and strontium oxides), and is shown connected between leads 18, 18 sealed through the end of the envelope. Provision for passing pulsating or A. C. current through the cathode coil 17 may be made by connecting its leads 18, 18 across the secondary of a transformer 20 whose primary is connected by leads 21, 21 across any suitable auxiliary power source *p*. The anode lead 16 and one of the cathode leads 18 are shown connected to a main power circuit 22 from any suitable pulsating or A. C. power source *P*. The envelope 14 may contain a low-pressure atmosphere of gas or vapor, or both, such as argon and mercury; or, preferably, the gas may consist of neon with a small admixture of argon—e. g., about 0.5% or 5%. A surplus supply of mercury is indicated by a drop 23 inside the envelope 14, and an internal coating of fluorescent material or phosphor 25 on the envelope walls is also indicated.

The pulsating or A. C. main voltage from source *P* should be sufficient, at or near its peak value, to sustain a discharge between the electrodes 15, 17, though not high enough to start one across so long a gap. The pulsating or A. C. auxiliary voltage from source *p* should not only be sufficient to heat the cathode 17 to electron-emissive temperature, but also high enough, at or near its peak value, to ionize the atmosphere in the device, thus producing an ionizing discharge along the cathode 17 between its leads 18, 18 which results in breakdown between the electrodes 15 and 17—or, in other words, fires the main discharge. The exact time or stage of its voltage cycle at which the main discharge thus fires may be varied and controlled either by varying the phase relation between the main and auxiliary voltages, or by varying the range and peak value of the auxiliary voltage wave, so as to change the point or stage in the auxiliary voltage cycle at which it reaches ionizing value, or both. Variation of the auxiliary voltage is perhaps the easier method; but variation of the phase relation affords a greater range of control. The range of phase adjustment ordinarily required is relatively small, so that the two voltage cycles may always be approximately in phase with one another. Adjustment of the point of main discharge ignition and of its duration in each voltage cycle may be helpful not

only to insure against runaway of the discharge, but as a means of adjusting the lumen output rating of a given fluorescent lamp. Furthermore, the luminous efficiency may be increased by reducing the wattage of the device, in this manner, below that resulting from the earliest ignition consistent with a positive characteristic.

Assuming that the sources P and p both furnish 60-cycle A. C., the main discharge between electrodes 15 and 17 will preferably be fired by the auxiliary discharge somewhat ahead of the crest of the main voltage peak of a half-cycle, and will persist till about the end of this half-cycle. This is indicated in Fig. 2 for the half-cycle I by the ordinate F_1 intersecting the main and auxiliary voltage curves V and v , and by the shaded area to the right of this ordinate under the curve V . As here shown, the auxiliary and main voltage cycles are exactly in phase, and both discharges fire the instant the auxiliary voltage reaches the ionizing potential of the discharge atmosphere, ahead of the crests of both voltage peaks. According to this diagram, in other words, the auxiliary voltage reaches and exceeds the ionizing potential E at the crests of its own peaks. Dying out when the main voltage falls to zero at the end of this half-cycle, at the point O , the main discharge remains out during next half-cycle II because there is no emissive cathode to support discharge in the reverse direction. During nearly or about half of the ensuing half-cycle III, the main discharge is still out, because the ionization from the previous discharges has decayed; but at the ordinate F_2 , somewhat ahead of the crest of this half-cycle III, the auxiliary discharge will again ionize the atmosphere in the device, and the main discharge will again fire exactly as in the first instance—as indicated by the shaded area to the right of F_2 . This quarter-cycle or quarter-wave operation continues indefinitely, as long as suitable pulsating or A. C. voltages are supplied from p and P , as is suggested by the ordinate F_3 .

Fig. 3 shows a pair of one-way discharge devices such as hereinbefore described reversely arranged and connected, rectifier fashion, so as to give approximate half-cycle operation as illustrated in Fig. 4. Fig. 4 also differs from Fig. 2 in showing the auxiliary voltage cycle as leading the main voltage cycle and firing on its own wave crests, instead of being in exact phase with the main voltage cycle and firing ahead of its own wave crests. According to Fig. 4, in other words, the auxiliary voltage only just reaches the ionizing potential E of the discharge atmosphere at the crests of its own peaks. In Figs. 3 and 4, various parts and features essentially corresponding to those in Figs. 1 and 2 are marked with similar reference characters, thus dispensing with repetitive descriptions. The principal point to be observed is that one of the discharge devices shown in Fig. 3 fires on the positive half-cycles, while the other fires on the negative half-cycles. Accordingly, the power factor is very much better for this combination than for a single device operating as illustrated in Figs. 1 and 2.

Half-cycle operation with its greatly improved power-factor can be obtained not only with two one-way discharge devices operated on 60-cycle A. C. as explained above in connection with Figs. 3 and 4, but with a single two-way discharge device such as shown in Fig. 5 operated on A. C. of approximately 25 cycle frequency, as from 20 to 30 cycles. This Fig. 5 device differs from that of Fig. 1 in having cathodes 17 at both ends, each with 75

one lead 18 connected to the main A. C. power circuit 22, so that each of these electrodes 17 functions alternately as cathode and as anode for the alternate main voltage half-waves, and also provides the auxiliary ionizing discharge for these half-waves. Accordingly, the same reference numerals are applied to various corresponding parts and features in Figs. 1, 3 and 5, as a means of dispensing with repetitive description. So closely, indeed, does this single Fig. 5 device correspond to the double Fig. 3 arrangement that its operation on 25-cycle A. C. is essentially represented by the same Fig. 4 diagram.

It is convenient, of course, that the main and auxiliary voltage and current sources P , p should be identical—i. e., that the auxiliary voltage should be derived from the main voltage. Such a simplification is illustrated in one form in Fig. 6, where the cathode 17 is connected across the main power circuit 22 in parallel with the electrodes 15, 17 by leads 21a, 21a and an interposed resistor 26, and in another form in Fig. 7, where the primary of the transformer 20 is connected by leads 21b, 21b across the main power circuit 22 in parallel with the electrodes 15, 17. A further variation is illustrated in Fig. 8, where the cathode 17c is shown as of indirectly heated type, comprising a heating coil 27 connected between the leads 18c, 18c and surrounded by an electron-emissive cylinder 28 coated with activating material 29. Here the auxiliary ionizing discharge takes place between the activated cathode surface 29 and a separate auxiliary anode 30, while the coil 27 is only a heater—the voltage through which preferably is not high enough to ionize. As here shown, the cathode cylinder 28 and one of the heating coil leads 18c are connected together and to one end of the secondary of the transformer 20c; the other lead 18c is connected to the midpoint of this secondary; and the auxiliary ionizing anode 30 is connected by a lead 31 to the other end of said secondary. Accordingly, the coil 27 receives only half the voltage across the transformer secondary; whereas the full secondary voltage is effective between the electrodes 17c and 30, and is just about sufficient, at or near the crest of its peak, to ionize the atmosphere and produce the auxiliary discharge.

The essentials for quarter-cycle operation on 60-cycle A. C. as described above are, of course, that the device should be able to conduct in but one direction, so as to fire only on alternate half-cycles; that the main discharge gap and voltage should be such that the device cannot fire on the firing half-cycles until ignited by the auxiliary ionizing discharge; and that this ignition be timed and limited (in either of the ways hereinbefore indicated) to occur some time during approximately the last 60% of the firing half-cycles. Even when the auxiliary and main discharges are energized from a common source P , as in Figs. 6, 7 and 8, the phase relation between the auxiliary and main voltages can be adjusted to time the ignition of the main discharge by various well-known means of displacing the derived auxiliary voltage out of phase with the main voltage, such as saturating transformers, chokes, or capacitors, for example.

A discharge device such as shown in Figs. 3, 6, and 7 may be built with an envelope tube 14 of 1 inch internal diameter 6 inches long; with an anode plate 15 of sheet molybdenum $\frac{1}{2}$ inch in diameter; with a cathode 17 consisting of an ordinary 15-watt fluorescent lamp cathode; and with a filling of argon at an absolute pressure of

4 mm. of mercury, plus a mercury droplet 23 ample to assure a surplus during operation. On 60-cycle A. C., such a device operates satisfactorily (without ballast) under a voltage of approximately 10 volts (root mean square) across the cathode circuit 18 and of 30 volts (root mean square) across the main power circuit 22, with a main discharge current of approximately 0.4 ampere. The R. M. S. voltages here stated correspond, of course, to substantially higher actual voltages at the peaks of the A. C. sine waves, as represented in Figs. 2 and 4. The main discharge current is very sensitive to small voltage changes, either in the main power circuit 22, or in the auxiliary circuit 18.

Besides the available voltage in the main power circuit 22, the practicable length of such a discharge device is limited by the distance to which ionization from the glow discharge at the cathode 17 will spread in the envelope tube 14. For a 1-inch tube charged with argon, the length limit is about 8 inches to nearly 12 inches; but it increases as the diameter of the tube 14 is increased, and is also greatly influenced by the composition of the atmosphere in the envelope 14: e. g., ionization extends much further in an atmosphere of neon with a small admixture of argon than in neon alone.

However, such limitations on tube length can in practice be overcome by means of ancillary ionizers at suitable intervals in the length of the tube, so that the zone of influence from one overlaps that of the next one; and the tube length can be as great as permitted by the available supply voltage. This is illustrated in Figs. 9-14, which show a few of the many possible arrangements and circuits.

Fig. 9 shows a one-way discharge device like that of Fig. 1, provided with an intermediate auxiliary anode 35 located within the ionizing range of the cathode 17, and close enough to the main anode 15 to bring the latter within ionizing range of the discharge between the electrodes 17 and 35. The electrode 35 is connected to the cathode side of the main power circuit 22 through the secondary of a leakage reactance transformer 36 whose primary is connected across the circuit 22. The transformer 36 is so selected that the voltage between cathode 17 and electrode 35 is sufficient to produce discharge across this gap when the atmosphere is ionized by the discharge along cathode 17; whereupon the ionization extends to the right-hand end of the tube and the discharge jumps to the main anode 15—thus short-circuiting and extinguishing or reducing to insignificant proportions the discharge between electrodes 17 and 35, owing to the resistance of the secondary of the transformer 36 in series with the electrode gap 17—35.

This Fig. 9 arrangement is peculiarly flexible because of the practically unlimited choice of starting voltage across the gap 17—35 that is afforded through the selection of the transformer 36: i. e., this starting voltage may, if desired, exceed the voltage of the source P by a wide margin. For example, a Fig. 9 tube of $1\frac{1}{8}$ inch internal diameter 54 inches long may be operated without ballast on a voltage of 160 volts across the electrode gap 17—15, using a voltage of 300 volts across the electrode gap 17—35 for starting.

The discharge device shown in Fig. 10 has an ancillary anode 35e located within the ionizing range of the auxiliary discharge at the cathode 17, and connected through a resistance 37 to the anode side of the main power circuit 22. Thus

the full value of the main voltage from source P is felt between the electrodes 17 and 35e until the gas is ionized by the discharge at the cathode 17, whereupon the device breaks down first to the ancillary anode 35e and then to the main anode 15, this discharge short-circuiting and thus extinguishing or reducing to insignificant proportions that between electrodes 17 and 35e, owing to the resistance 37.

10 The discharge device shown in Fig. 11 involves a cumulative reduplication of the Fig. 10 arrangement: i. e., the discharge between electrodes 17 and 35e jumps first to another ancillary anode 35f and then to the main anode 15, successively 15 short-circuiting and reducing or extinguishing the discharges between electrodes 17 and 35e, 35f, owing to the resistances 37 and 37f.

15 The discharge device shown in Fig. 12 has two ancillary electrodes 35g and 38 connected through resistances 37g and 39 to the opposite sides of the main power circuit 22. The full value of the main voltage from source P is felt between electrodes 35g and 38 until ionization of the atmosphere by the discharge at the cathode 17. Thereupon discharge occurs across the electrodes 35g and 38, then jumps to the electrodes 17 and 15, short-circuiting and reducing the discharge between 35g and 38, owing to resistances 37g and 39.

20 Fig. 13 shows a device which combines essential features of Figs. 6, 8 and 10 in a simplified form. Its cathode 17h is of indirectly heated type like that in Fig. 8, with its coil 27h (which merely heats, without having any ionizing discharge along it) connected in a circuit 21h across the main power circuit 22, and its cathode tube 28h grounded to one of the coil leads 18h. It has an auxiliary ionizing anode 30h connected to the anode side of the main power circuit 22 through a lead including a resistance 31h such that the voltage of discharge across the electrodes 17h, 30h is just about sufficient to ionize the discharge atmosphere at or near the crest of its peak. Its ancillary ionizing anode 35h and its connections may be essentially like the parts designated by the same reference numerals in Fig. 10. In order to dispense with repetitive description, corresponding parts and features in Figs. 6, 8, 10 and 13 are marked with the same reference numerals—a distinctive letter being added where such distinction appears necessary.

25 The device shown in Fig. 14 resembles that of Fig. 13, but differs as regards the cathode of 17j and the auxiliary electrode 30j: i. e., the cathode 17j is shown of the cold-starting activated coil type, like that of an ordinary fluorescent lamp, and the auxiliary anode 30j is located close to it and connected to the anode side of the circuit through a resistance 31j. Thus the full value of the main voltage from source P is initially felt between the electrodes 17j and 31j, and suffices for cold-cathode initiation of discharge between them. Once this discharge is started, its voltage is reduced to substantially the ionizing potential of the atmosphere by the resistance 31j, and it continues as an auxiliary ionizing discharge like that in the Fig. 1 and other devices, igniting the main discharge at the proper points on the firing half-waves. If the desired length of the device 30 requires, the ancillary electrode 35j with its resistance connection 37j may be provided, operating just like the corresponding parts in Figs. 10, 11 and 13. To dispense with repetitive description, corresponding parts and features in Figs. 10, 11, 13 and 14 are marked with the same refer-

ence numerals, distinctive letters being added where distinction seems necessary.

What I claim as new and desire to secure by Letters Patent of the United States is:

1. A method of producing and controlling intermittent electric discharge through an ionizable atmosphere; which method comprises applying across a main discharge gap between electrodes in said atmosphere a main pulsating voltage of peak value sufficient to sustain discharge across said gap, but insufficient to initiate such discharge; intermittently applying across a gap between electrodes in said atmosphere an ionizing potential sufficient to initiate a discharge thereacross, which ionizes said atmosphere and thus ignites a main discharge pulse under said main pulsating voltage; and timing the intermittent application of said ionizing potential to allow the ionization accompanying each main discharge pulse ignited as aforesaid to die out before ignition of the next succeeding main discharge pulse.

2. A method of producing and controlling intermittent electric discharge through an ionizable atmosphere; which method comprises applying across a main discharge gap between electrodes in said atmosphere a main pulsating voltage of peak value sufficient to sustain discharge across said gap, but insufficient to initiate such discharge; intermittently applying across a substantially shorter gap between electrodes in said atmosphere an ionizing potential sufficient to initiate a discharge across said shorter gap, which ionizes said atmosphere and thus ignites a main discharge pulse under said main pulsating voltage; and timing the intermittent application of said ionizing potential to allow the ionization accompanying each main discharge pulse ignited as aforesaid to die out before ignition of the next succeeding main discharge pulse.

3. A method of producing and controlling intermittent electric discharge through an ionizable atmosphere; which method comprises applying across a main discharge gap between electrodes in said atmosphere a main A. C. voltage of peak value sufficient to sustain discharge across said gap, but insufficient to initiate such discharge; applying across a substantially shorter gap between electrodes in said atmosphere an A. C. ionizing potential of peak value sufficient to initiate a discharge across said shorter gap, which ionizes said atmosphere and thus ignites a main discharge pulse under said main A. C. voltage; and timing the cycles of said A. C. ionizing potential to allow the ionization accompanying each main discharge pulse ignited as aforesaid to die out before ignition of the next succeeding main discharge pulse.

4. A method of producing and controlling intermittent electric discharge through an ionizable atmosphere; which method comprises applying across a main discharge gap between electrodes in said atmosphere a main pulsating voltage of peak value sufficient to sustain discharge across said gap, but insufficient to initiate such discharge; intermittently applying across a substantially shorter gap between electrodes in said atmosphere a substantially lower potential pulsating voltage approximately in phase with the pulsations of the first-mentioned voltage, and reaching the ionizing potential of the atmosphere only on its peaks, which thus ionize said atmosphere and ignite main discharge pulses under said main pulsating voltage; and timing the intermittent application of said ionizing potential

to allow the ionization accompanying each main discharge pulse ignited as aforesaid to die out before ignition of the next succeeding main discharge pulse.

5. A method of producing and controlling intermittent electric discharge through an ionizable atmosphere; which method comprises applying across a gap between main one-way discharge electrodes in said atmosphere a 60-cycle voltage peak value sufficient to sustain discharge across said gap, but insufficient to initiate such discharge; intermittently applying across an auxiliary gap between electrodes in said atmosphere, near the peaks of said 60-cycle voltage in the direction of discharge permitted by said one-way discharge electrodes, an ionizing potential sufficient to initiate a discharge across said auxiliary gap which ionizes said atmosphere and thus ignites a main discharge pulse between said one-way discharge electrodes; and timing the intermittent application of said ionizing potential to allow the ionization accompanying each main discharge pulse ignited as aforesaid to die out before ignition of the next succeeding main discharge pulse.

6. A method of producing and controlling intermittent electric discharge through an ionizable atmosphere; which method comprises applying across a gap between main two-way discharge electrodes in said atmosphere a voltage of frequency approximating 25 cycles and of peak value sufficient to sustain discharge across said gap, but insufficient to initiate such discharge; intermittently applying across an auxiliary gap between electrodes in said atmosphere, near the peaks of said voltage in both directions, an ionizing potential sufficient to initiate a discharge across said auxiliary gap which ionizes said atmosphere and thus ignites a main discharge pulse between said main discharge electrodes; and timing the intermittent application of said ionizing potential to allow the ionization accompanying each main discharge pulse ignited as aforesaid to die out before ignition of the next succeeding main discharge pulse.

7. In combination, an electric discharge device comprising an envelope containing an ionizable atmosphere, and electrodes therein; means for applying between electrodes aforesaid a main pulsating voltage of peak value sufficient to sustain discharge across their gap, but insufficient to initiate such discharge; and means for intermittently applying between electrodes aforesaid an ionizing potential sufficient to initiate a discharge thereacross, which ionizes said atmosphere and thus ignites a main discharge pulse under said main pulsating voltage, the intermittent application of ionizing potential being timed to allow the ionization accompanying each main discharge pulse ignited as aforesaid to die out before ignition of the next succeeding main discharge pulse.

8. In combination, an electric discharge device comprising an envelope containing an ionizable atmosphere, and electrodes therein affording a main discharge gap and a substantially shorter auxiliary discharge gap; means for applying across said main discharge gap a main pulsating voltage of peak value sufficient to sustain discharge across said gap, but insufficient to initiate such discharge; and means for intermittently applying across said auxiliary discharge gap an ionizing potential sufficient to initiate a discharge thereacross, which ionizes said atmosphere and thus ignites a main discharge pulse across said

main discharge gap, the intermittent application of ionizing potential being timed to allow the ionization accompanying each main discharge pulse ignited as aforesaid to die out before ignition of the next succeeding main discharge pulse.

9. In combination, an electric discharge device comprising an envelope containing an ionizable atmosphere, and electrodes therein affording a one-way main discharge gap and a substantially shorter auxiliary discharge gap; means for applying across said one-way discharge gap a main A. C. voltage of peak value sufficient to sustain discharge across said gap, but insufficient to initiate such discharge; and means for applying

across said shorter discharge gap, during periods of the main A. C. voltage cycles when the direction of the main A. C. voltage makes discharge possible across the one-way gap, a substantially lower A. C. ionizing potential of peak value sufficient to initiate a discharge across said shorter gap which ionizes said atmosphere and thus ignites a main discharge pulse across said one-way gap, the cycles of said A. C. ionizing potential being timed to allow the ionization accompanying each main discharge pulse ignited as aforesaid to die out before ignition of the next succeeding main discharge pulse.

EUGENE LEMMERS.
